[57] CLAIM

The ornamental design for a combined bingo bag kit and seat pad, substantially as shown and described.

DESCRIPTION

FIG. 1 is a front perspective view of a combined bingo bag kit and seat pad showing my new design;

FIG. 2 is a bottom rear perspective view thereof;

FIG. 3 is a perspective view thereof in the open position showing bingo paraphernalia stored therein;

FIG. 4 is a perspective view thereof opened for use as a seat pad; and

FIG. 5 is an enlarged scale cross-sectional view taken along line 5—5 of FIG. 1.
